IMPROVEMENT IN TABLES FOR CONCENTRATING ORES.

HENRY ALDERSON THOMPSON, OF GRANT, GIPPS LAND, VICTORIA.

Letters Patent No. 60,089, dated November 27, 1866.

SPECIFICATION.

TO ALL WHOM IT MAY CONCERN:

Be it known that I, HENRY ALDERSON THOMPSON, of Grant, Gipps Land, British colony Victoria, have invented a new and improved Percussion Table for Concentrating and Dressing Ores; and I do hereby declare that the following is a full, clear, and exact description thereof, which will enable others skilled in the art to make and use the same, reference being had to the accompanying drawings, forming part of this specification.

The object of this invention is to provide a table for concentrating and dressing ores, on which the material is kept in a loose state by means of stirrers, thus allowing a more perfect concentration with less loss at one dressing than can be obtained on the plan now generally used by means of several dressings.

In the percussion table now largely used in ore-dressing, the material on the table forms a hard bank, which impedes the tendency of the heavier ores to concentrate, and consequently the sands or slimes operated on have to be dressed several times before they are brought to a sufficient degree of richness. This repeated dressing adds considerably to the expense, and in each manipulation a loss of ore occurs. These drawbacks render the percussion table in its present form inapplicable to the separation of gold ores. By my invention these defects are completely overcome. To make the same more clearly understood, I will now proceed to describe my apparatus and the mode of operating it, reference being had to the annexed drawing, in which—

Figure 1 represents a side elevation of my improved table, the side supports, N, being removed.

Figure 2 is an end view; and

Figure 3 an isometrical perspective view of the same.

Figure 4 is a cross-section through the stirrers, P Q, and their supports, O and N, taken on the line *x x*, fig. 1.

Figure 5 is a cross-section through the stirrer head, P, taken on the line *y y*, fig. 4.

Similar letters of reference indicate like parts.

A is the ordinary framework. B is the percussion table, of sufficient length and width, its upper surface covered with boiler plate. The table, B, is enclosed on the sides with boards, D, which gradually incline upwards near the head, C, said head being a solid wooden block, its sides of a triangular shape, its surface being inclined at an angle of about 22°, as seen in figs. 1 and 3. The table is supported or hung on four chains, E, with regulating screws on each in order to adjust the lateral level of the table. The chains at the foot of the table pass over rollers, F, fixed to the frame and acted upon by levers, G, as shown, for the purpose of raising and lowering that end of the table. The head-chains are attached to a rack, H, in order to permit the changing of the inclination of the chains, as by an increased inclination of the chain the table is brought back with a sharper blow, and the effect of the percussion increased. I is the distributing-board, having the usual triangular distributing-blocks, upon which board the material to be treated is fed. L, a cam working on a cam-shaft which is made to revolve with the required velocity, so that the cam strikes the lever, K, working on its axis, *a*, whereby the upper end of the lever, K, is pushed from the framing, while its lower end, which rests against the head, C, of the table, pushes the said table away from the block, M, to the extent of the stroke of the cam. By its own gravity the table then falls back against the block, and thus receives the percussion blow. To the frame, A, are attached side-bearers, N, which act as supports for the stirrer frame, O, as shown in fig. 4. P are transverse bars, provided with pins at their ends hanging loosely in their bearings, O. To these bars are attached the stirrers, Q, which are made of wire rods, of appropriate length, their ends being slightly curved, as seen in fig. 5, for the purpose of better sliding on the table, B. Two screws, R, pass through the main frame, and are operated by handles, S. These screws are for the purpose of pushing the stirrer frame or bars, O, nearer to the head of the table, or *vice versa*, as may be required; so that, should, for instance, the stroke of the table be lessened, then it would be necessary that the stirrers should be nearer to the head than before.

I will now proceed to describe the operation of my apparatus: The lower end of the table is first raised about one inch above the level by means of the roller, F, operated by levers, G. The distributing-board is then supplied with material and with the necessary amount of water until there is about two and a half inches of depth of material at the lower end of the incline formed by the head, C. The table is then gradually lowered in such a manner as to preserve constantly this depth of material. When the table is sufficiently charged with the material concentrated, the supply is cut off and a stream of water is admitted at the rate of about twelve gallons per minute, and continued until there is a good concentration of material at the head of the table, the foot of the table having in the meantime been gradually lowered sufficiently to allow of the waste material being washed away, such lowering being in no case to a greater extent than about one inch below the

level. The supply of clean water is then cut off and the action of the table stopped. The transverse pieces 1, 2, and 3 are lifted out, and the material lying on the table from whence they have been removed is taken out and subjected to suitable treatment for the extraction of the precious metals. The stirrers 1, 2, and 3 are then replaced, the foot of the table is elevated about three inches above the level, the percussive action of the table is renewed, and the distributing-board is again supplied with fresh material. The result is that the material which remained on the table returns after a few percussions to the head, where it is again subjected to the action of the table, together with the fresh material. The foot of the table is then gradually lowered as before, always preserving the two and a half inches depth of material at the head, as stated above. Instead of working continuously, as just described, it may be preferable or necessary to work in charges. In this case the lower end of the table must be raised sufficiently high to allow the table to hold the charge, which should be placed at the head, as much water being continuously supplied as would keep the material loose. The table is then put in motion and kept at work until the valuable material is concentrated at the head, when the foot is gradually lowered and the waste material washed off with an increased supply of water; the front stirrers may then be lifted out and the material removed as before.

Having thus described my invention, I claim as new, and desire to secure by Letters Patent—

The combination of the frame A, supports N, and screws R, with the table B, stirrers Q, and stirrer frame O, substantially as and for the purposes herein shown and described.

The above specification of my invention signed by me this 26th day of July, 1866.

HENRY ALDERSON THOMPSON.
